UNITED STATES PATENT OFFICE.

JOHN GROSSGEBAUER, OF PATERSON, NEW JERSEY.

DESIGN FOR A RIBBON.

47,720.

Specification for Design.

Patented Aug. 17, 1915.

Application filed June 16, 1915. Serial No. 34,531. Term of patent 7 years.

To all whom it may concern:

Be it known that I, JOHN GROSSGEBAUER, a citizen of the United States, residing in the city of Paterson, county of Passaic, State of New Jersey, have invented a new, original, and ornamental Design for a Ribbon, of which the following is a specification, reference being had to the accompanying drawings, forming a part thereof.

The figure is a plan view of a piece of the ribbon, illustrating my new design.

The design consists of representations of doves holding in their bills an olive branch or festoon.

I claim:

The ornamental design for a ribbon, substantially as herein described and shown.

JOHN GROSSGEBAUER.
